UNITED STATES PATENT OFFICE.

WALLACE I. STIMPSON, OF HOPEDALE, MASSACHUSETTS, ASSIGNOR TO DRAPER CORPORATION, OF HOPEDALE, MASSACHUSETTS, A CORPORATION OF MAINE.

AUTOMATICALLY-THREADING SHUTTLE.

Application filed July 10, 1925. Serial No. 42,753.

To all whom it may concern:

Be it known that I, WALLACE I. STIMPSON, a citizen of the United States, residing at Hopedale, in the county of Worcester and State of Massachusetts, have invented an Improvement in Automatically-Threading Shuttles, of which the following description, in connection with the accompanying drawings, is a specification, like characters on the drawings representing like parts.

This invention relates to automatically threading loom shuttles which are replenished from time to time during the weaving operation.

It is now the usual practice to provide filling replenishing looms with a hopper containing filling carriers or bobbins having filling thread wound thereon, the ends of which are secured to a fixed point, and to employ in connection therewith shuttles having means which seek to take control of the thread or "thread the shuttle" as it is picked, and thereafter prevent unthreading. The first of these problems has presented much difficulty and uncertainty due to the overhangs, guards, projections and the like, which have been employed to prevent subsequent unthreading.

When the shuttle is picked following replenishing, the lay is back from the position it occupied during replenishment, with the result that the overhangs, guards, and projections, heretofore used and extending from the sides of the thread passage, have interfered with the natural swirling movement of the thread as it is withdrawn from the shuttle and often prevented the threading devices from securing control of the thread, which would consequently break on the return pick of the shuttle. In attempts to overcome this difficulty, the wood of the shuttle has been grooved or cut away forward of the threading block, and while such expedients have succeeded to some extent in securing partial threading of the shuttle, they have failed to prevent unthreading by the weft fork on the beat up following replenishment when the shuttle, only partially threaded, is in the non-replenishing shuttle box.

The present invention overcomes the difficulties heretofore experienced, and provides an automatically threading loom shuttle with a longitudinally extending thread

passage open at its top at both sides of the longitudinal axis of the shuttle and offering no obstruction to the natural swirling action of the thread at or adjacent to the bobbin chamber, and as contributing to the preliminary threading of the shuttle as it is picked following replenishment and the permanency of thread control, the shuttle wood is provided with a thread leader of novel construction extending diagonally from the tip of the shuttle to the thread passage.

In accordance with the present invention, the threading block has a thread director at the front of the open thread passage which is provided with a thread catch cooperating with the thread leader to prevent unthreading of the shuttle by the weft fork on the beat up following replenishment when the shuttle is in the non-replenishing box.

The invention and novel features thereof will best be made clear from the following description and the accompanying drawings of one good form thereof.

In the drawings:

Fig. 1 is a plan view of the threading end of a shuttle provided with the present invention;

Fig. 2 is a perspective view of some of the loom parts and the shuttle, showing the relation thereof on the beat up following replenishment and during the action of the weft fork;

Fig. 3 is a plan view of a shuttle embodying the present invention, showing the shuttle as being completely threaded;

Fig. 4 is a front end view of the threading block showing the swirling action of the thread about either of two centers in the thread passage;

Fig. 5 is an enlarged section on the line 5-5 of Fig. 3; and

Fig. 6 is an enlarged perspective view of the threading end of the shuttle showing the thread catch and the lead of the thread therefrom when the shuttle is partially threaded.

The shuttle body 1 is preferably formed of wood and contains the usual bobbin chamber 2 open at the top and bottom for replenishing purposes, as usual. Within the bobbin chamber 2 is the filling carrier or bobbin 3, having the filling wound there-

on, and detachably held by the usual bobbin holding jaws (not shown) for filling replenishing purposes.

Frontward of the bobbin chamber 2 the shuttle is provided with a threading block receiving chamber 4 in which is secured the threading block 5 as by the usual cross-bolt 6. Extending longitudinally of the threading block 5 is the thread passage 7 which, as shown, is open at its top and offers no obstruction to the swirling action of the thread as it is withdrawn from the filling carrier or bobbin during the flight of the shuttle. The side walls 8 and 9 of the threading block extend upwardly from the base portion of the block at the sides of the block receiving chamber 4, and at the side of the shuttle adjacent the side delivery eye 10 the threading block is provided with a thread director 11, the front end portion 12 of which is extended laterally of the threading block receiving chamber 4 in a transverse direction relative to the longitudinal axis of the shuttle.

25 The threading block 7 at the front is provided with a bridge 13, the center portion of which is depressed at 14 centrally of the shuttle or in the longitudinal axis thereof, and affords a guide for the filling thread *a* from the bridge through the side delivery eye 10, as indicated in Fig. 3. Between the front edge portion 15 of the thread director and the wood 16 of the shuttle, the usual passageway is provided for the thread on its course to the side delivery eye during complete threading of the shuttle.

The shuttle body 1 is provided with a thread leader 17 which extends from a point 18 at one side near the tip end portion of the shuttle in a diagonal direction to the point 19 where it joins the longitudinal thread passage. The thread leader 17 has a rounded lower surface 20 which extends between the points 18 and 19 and is preferably formed in a circular curve corresponding to the swirling action of the thread during its flight following replenishment of filling. The side of the thread leader adjacent the side delivery eye is carried upward in a rounded curve, as at 21, to guide the thread into the passageway leading to the side delivery eye, while the opposite wall 22 gradually rises from the end portion 18 of the leader towards the end of the thread director in a surface curve corresponding to the path of the swirling thread *a* against which the thread strikes and by which it is guided to the control of the thread director, indicated in Fig. 5, as the shuttle is picked following replenishment of filling.

60 The surface curve of the wall 22 of the thread leader is continued upwardly and over the end of the thread director as at 22^x in the form of an overhang which, as will further appear, not only directs the swirling

thread to insure preliminary threading, but once such preliminary threading is effected, acts in conjunction with the thread catch, to be described, to prevent unthreading, either by the action of the thread itself or by the weft fork on the following beat up.

65 The end of the thread director is provided with a thread catch 23 which extends downwardly from the end of the director in close proximity to the curved surface 22 of the thread leader and has its outer surface 23^x rounded in a downward curve close to and corresponding with the surface curve 22 of the thread leader. The thread catch 23 is undercut or provided with a guide 24 at the side adjacent the side delivery eye into which the thread naturally swings as the shuttle is picked following replenishment, the relation of the thread catch and the thread leader being such that once the thread is engaged with the thread catch, it is thereafter prevented from disengagement therefrom or unthreading of the shuttle.

70 When replenishment is effected, the lay is in its front position, but when the shuttle is picked the lay is at or near its back position, the result being that the thread leader in the present invention is diagonally arranged with relation to the longitudinal axis of the shuttle, such that the lead of the filling thread from the point of its attachment to the shuttle will naturally occupy the thread leader. As the shuttle is picked following replenishment, the thread will swirl or balloon from the filling carrier in the shuttle around the fixed point to which the filling is attached, and in such swirling movement, due to the direction of the thread leader, the swirling thread *a* will engage the surface of the thread leader and be by it directed downwardly into the bottom portion of the thread leader and on its upward rise will naturally swing into engagement with the thread catch 23, as indicated in Fig. 5. Once the thread has been caught by the thread catch during its flight after replenishment the swirling action of the thread, as it is unwound from the bobbin, as indicated by full lines in Fig. 1, will center about the thread catch 23, and inasmuch as there is no obstruction in the thread passage for such swirling action, the thread is free to take its natural course. When, however, the shuttle is returned to the replenishing box, the thread will pass through the guideway along the edge of the thread director into the side delivery eye, as indicated in Fig. 3, and at such time will bear upon the recessed portion of the bridge 13 in the threading block, with the result that the thread may now swirl or balloon as it is drawn from the bobbin about the bridge as a center, as indicated by dotted lines in Fig. 1 and by full lines in Fig. 3.

When the partially threaded shuttle

reaches the non-replenishing box and the lay beats up, the shuttle is partially threaded: that is, the thread *a* is caught by the thread catch 23 and leads to the fixed 5 point where all of the threads in the hopper are secured. As the lay 25 beats up, the filling fork 26 engages the thread, as indicated in Fig. 2, with the result that the thread *a* is pushed back and upwardly from the 10 thread leader, but owing to the rise and overhang of the thread leader above the downturned thread catch, no tendency is exerted for disturbing the engagement of the thread with the thread catch. This is due to two 15 causes; first the character of the catch itself, and second, its relation to the walls of the thread leader which causes an abrupt rise in the thread from the thread catch over the top of the wall of the thread leader, as 20 indicated in Fig. 2.

Since the longitudinally extending thread passage leading from the bobbin chamber offers no obstruction to the natural swirl of the thread when it is first picked following 25 replenishment, such swirl extends substantially throughout the entire length of the thread to the point of attachment at the hopper, and the thread in its circular path engages the abrupt wall 22 of the 30 thread leader and is directed by its natural swirl into engagement with the thread catch, as indicated at 25. When once engaged with the thread catch, the swirling action of the thread will take place about the 35 thread catch as a center on the first pick of the shuttle following replenishment, and on the next excursion of the shuttle towards the replenishing box the thread *a* will be guided into the side delivery eye, as indicated in Fig. 3, and at such time the 40 thread may swirl or balloon freely in the thread passage about the bridge 13 as a center.

From the construction described it will be 45 understood that the free natural swing or swirl of the thread finds no obstruction in the open thread passage as the shuttle is picked from the replenishing box after replenishment, and such natural swirl of the 50 thread insures the preliminary threading of the shuttle or the engagement of the thread by the thread catch due to the directing influence of the diagonally arranged and abrupt wall of the thread leader which extends in a direction substantially coincident with a line between the thread catch and the 55 point of attachment of the threads, and the wall of the thread leader further insures that when the shuttle is partially threaded, the action of the weft fork in pushing back the 60 thread, causes it to remain in positive engagement with the thread catch as it rises over the top of the wall of the thread leader.

65 During subsequent weaving when the

shuttle is fully threaded, should a loop occur and be thrown to the side of the shuttle opposite the side delivery eye, the wall of the thread leader will still maintain the thread in engagement with the thread catch, 70 and should the loop throw to the opposite side of the shuttle or towards the side delivery eye, no tendency will be exerted to throw the thread from the control of the thread catch, so that on the subsequent pick 75 of the shuttle it will again be fully threaded.

As the thread swirls between the bobbin and fixed point of the hopper, the wide open thread passage presents no obstruction to the natural movement of the thread which 80 will balloon as it leaves the bobbin and effect partial threading of the shuttle, as described, before it reaches the non-replenishing box, after which unthreading of the shuttle is prevented by the cooperating control of the thread leader and thread catch, even though the weight of the weft fork is such as to carry the thread backward during the following beat up. The absence of the usual guards and overhangs at the top of 85 the thread passage permits the thread to swirl in its natural path without obstruction and through such thread movement insures shuttle threading which is not the case when the thread movement is obstructed. 90

To control or limit the swirling action of the thread as it is withdrawn from the bobbin during weaving, it is sometimes desirable to provide means to confine the initiation of the swirl to a point adjacent the 95 end of the bobbin, and in the present instance such means is shown as a brush or bristles 27 secured to the shuttle and extending into engagement with or closely adjacent to the end portion of the bobbin, as indicated in Fig. 1. When such means is employed, the swirling action of the thread commences at or adjacent the tip end of the 100 bobbin.

What is claimed is:

1. In an automatically threading shuttle for looms, the combination of the shuttle body having a longitudinally extending thread passage and side delivery eye, a bridge over which the thread passes to the side delivery eye and constituting the ballooning center for the thread in the thread passage during weaving when the shuttle is completely threaded, a thread director forward of the side delivery eye and having a thread catch constituting the ballooning center for the thread during weaving when the shuttle is only partially threaded. 115

2. In an automatically threading loom shuttle, the combination of the shuttle body having a thread director and a longitudinally extending thread passage rearward thereof constructed and arranged to permit the natural swirling movement of the thread in the thread passage about a center trans- 120 125 130

- versely adjacent the side delivery eye when the shuttle is completely threaded during weaving and about the end portion of the thread director when the shuttle is only 65 partially threaded during weaving, and means to prevent the escape of the thread from the control of the director when the thread balloons about the end of the director as a center.
- 10 3. An automatically threading loom shuttle having a side delivery eye and a longitudinally extending thread passage constructed and arranged to permit the thread to swirl or balloon naturally from the filling 70 carrier to insure shuttle threading as the shuttle is picked following replenishment, and a thread director for directing the thread to the side delivery eye as the shuttle is again picked in the opposite direction 75 and provided with a thread catch to retain control of the thread when the shuttle is partially threaded.
4. In an automatically threading loom shuttle, a threading block provided with a 25 longitudinal thread passage having a top opening coextensive with the thread passage to permit free unobstructed swirling movement of the thread, a thread director provided with a thread catch extending down 30 from the end of the director and about which as a center the thread may balloon when the shuttle is picked and is partially unthreaded.
5. An automatically threading loom shuttle having a side delivery eye provided with a threading block having a thread passage extending longitudinally of the shuttle and an open top coextensive in width with the thread passage to permit free swirling or 40 ballooning movement of the thread as the shuttle is picked following replenishment, a thread director for directing the thread to the side delivery eye on the following pick and having a downwardly extending 45 thread catch at its end which prevents unthreading of the shuttle when once the thread is engaged by the catch.
6. An automatically threading loom shuttle having a side delivery eye, a threading 50 block having a longitudinally extending thread passage and a wide open top for the unobstructed entrance of the thread as the shuttle is picked, a thread director having a thread catch, a thread leader formed in the 55 wood of the shuttle frontward of the threading block and provided with an abrupt wall over which the thread may be deflected by the weft fork to prevent unthreading.
7. An automatically threading loom shuttle having an unobstructed thread passage 60 in which the thread may swirl or balloon as the shuttle is picked to insure shuttle threading and a thread director for directing the thread to the side delivery eye as the shuttle is again picked. 65
8. An automatically threading loom shuttle having an unobstructed thread passage in which the thread may swirl or balloon as the shuttle is picked, a thread leader formed in the wood of the shuttle and extending diagonally in substantially the lead of the thread as the shuttle is picked following replenishment, the rear wall of the leader rising abruptly, and a thread director having a thread catch to engage the thread 70 as it is deflected by the abrupt wall due to the swirling movement of the thread as it is withdrawn from the shuttle. 75
9. An automatically threading loom shuttle having a longitudinally extending thread 80 passage provided with an open top substantially the width of the thread passage and offering no obstruction to the natural swirling movement of the thread as it is withdrawn from the shuttle, and a thread director having a thread catch for engagement of the thread due to thread movement as the shuttle is picked following replenishment. 85
10. An automatically threading loom shuttle having an open longitudinally extending thread passage offering no obstruction to the swirling movement of the thread as the shuttle is picked, a thread director having a downwardly extending thread 90 catch, and a thread leader formed in the shuttle wood and having a surface curve in conformation with the swirling movement of the thread as it is picked following replenishment and provided with an overhang above the thread catch to prevent unthreading by the weft fork on the beat up 95 following replenishment. 100
11. An automatically threading loom shuttle having an open thread passage offering no obstruction to the swirling movement of the thread during weaving, a thread leader formed in the shuttle wood in the direction of the lead of the thread following replenishment and provided with a surface curved in conformity with the swirling path of the thread which terminates adjacent the thread passage in an overhang, and a thread director having a thread catch extending downwardly therefrom beneath the overhang and provided with its outer surface curved in conformity with the curve of and adjacent to the rear wall of the thread leader. 110
- 120 In testimony whereof, I have signed my name to this specification.

WALLACE I. STIMPSON.
